ADJUSTABLE TELESCOPING TRANSFORMER WITH A LOOP CORE

James A. Anderson, Memphis, Tenn.

Application June 4, 1951, Serial No. 229,781

3 Claims. (Cl. 336—117)

1

This invention relates to adjustable transformers for alternating current load circuits of all types and, although not limited to this type, the invention is especially suitable for transformers used in arc welding circuits. The invention is more specifically related to regulating transformers of the "induction" type in which the current drawn from the secondary winding of the transformer may be controlled by controlling the ratio of transformation.

The main object of the invention consists in providing a transformer of the induction type with a wide range of regulability of the secondary current and of great simplicity of construction in which the transformer ratio may be adjusted with high precision.

A further principal object of the invention consists in using a closed transformer core or frame without gap or interruption and without auxiliary structure for the purpose above mentioned.

Transformers permitting fine regulation and more specifically transformers of this type which are used for arc welding are most frequently of the "reluctance" type in which the desired regulation is obtained by a change in the magnetic reluctance of the transformer core or of adjoining auxiliary structures. In these constructions the magnetic flux passing through the transformer core also passes through an adjustable gap the width of which regulates the reluctance of the magnetic circuit. Alternatively the reluctance may be varied by means of variable magnetic shunts or by means of variable auxiliary magnetic circuits. This type of transformer, however, does not have a wide range of adjustability. Moreover the transformers of this type usually have a rather involved construction, as secondary cores and other auxiliary elements have to be used and as a section of the rather heavy and bulky transformer core or frame or an auxiliary or secondary core have to be moved.

Transformers of the induction type have a much wider range of adjustability, but the known types also show a rather involved construction as they usually are provided with a counterbalanced secondary coil which is moved towards the primary coil, the latter being mounted on an auxiliary core projecting from the main transformer core in order to permit such relative motion of the secondary coil. These known constructions therefore have the disadvantage that an extraneous construction must be used for supporting the secondary coil and for producing a swinging movement of the same towards the primary coil and moreover the core construction is usually of a complex type in order to accommodate the primary coil in a suitable position.

According to the invention the primary and secondary coils are both mounted on the same leg of a completely closed transformer frame and are moved relatively to each other along the said leg. One of the transformer coils is provided with an annular winding of such a size that it

2

permits to accommodate the other coil in its interior. Preferably only one of the coils is movable while the other coil is fixed and the movement is imparted to the movable coil by attaching it to the movable member of a helical or worm gear sliding in a direction which is parallel to the transformer leg on which the two coils are mounted. The ratio of transformation may thus be adjusted within relatively wide limits while the efficiency of the transformer remains high on account of the fact that both coils are centered on the same leg of a closed transformer and that there are therefore no stray fields which cause losses.

15 Further objects of the invention will be explained in detail in the following specification.

The invention is illustrated in the accompanying drawings showing one embodiment thereof by way of example. It is however to be understood that the example shown has been selected for the purpose of explaining the principle of the invention and the best mode of applying said principle and that other modes of applying the same principle can be readily designed by experts skilled in the art on the basis of the disclosure made in the specification. A departure from the example shown in the drawing is therefore not necessarily a departure from the principle of the invention.

30 In the drawings:

Figure 1 is an elevational view of the transformer assembly;

Figure 2 is an elevational sectional view of the transformer assembly, the section being taken 35 along line 2—2 of Figure 1;

Figure 3 is a sectional view of a detail, the section being taken along line 3—3 of Figure 1;

Figure 4 is a sectional view of a detail, the section being taken along line 4—4 of Figure 1.

40 As above explained, the transformer according to the invention, comprises a completely closed laminated core frame 10, without gap or interruption on which the primary and secondary transformer coils are directly mounted. The core 10 has the shape of an oblong closed frame with parallel longitudinal legs 11, 19 and with parallel transverse legs 13 joining the longitudinal legs. The primary and secondary coils 12 and 15 are mounted on the same transformer leg 11 and one of said coils (12 in Figure 1) may

45 be mounted fixedly on the frame or on a support or part to which the frame is attached. This coil, in the example shown, is of a larger diameter than the other coil 15. The spool 14 of the coil has a hollow interior of sufficient size to accommodate the smaller coil 15 which may therefore be moved partly or completely into the space encircled by the larger coil 12.

While the lamellae of the laminated transformer core or frame may be held in the usual manner on the legs 13 and 19 special clamping and guiding plates, indicated at 22, may be used in connection with the leg 11. These plates may serve as a guide for the movable coil, the spool

of which may have recesses 26 for accommodating said plates. These guiding plates will assist in producing a smooth movement of the coil without jamming.

The movable coil 15 is mounted on a spool 24 which may be provided with the above mentioned recesses 26 which are filled by the guiding plates 22. The spool 24 carries the winding of the transformer in the conventional manner. It may be provided with flanges 24 and on one of said flanges an angular bracket 16 is fixedly mounted which carries a bolt 17 passing through a bore in said angular bracket, which bolt projects from a yoke member 18. The yoke member is provided with parallel side plates having bores through which a shaft 30 may pass. This shaft is either a square shaft or may be a round shaft provided with a key 32. Within the yoke and between the side plates of the same a worm wheel 20 is arranged which is mounted on said shaft 30 and which is secured on said shaft by means of the key 32 so that it is rotated with the shaft. Preferably, the worm wheel fits into the space between the two side plates of the yoke member 18 and it is thus axially held within said yoke member.

The worm wheel meshes with a rack 33 which is mounted on the inside of the leg 19 of the transformer frame which faces the leg 11. The rack 33 may be held on the leg 19 by means of clamps 34 which may also carry the bearing blocks 36 for shaft 30.

The shaft 30 preferably is stepped so as to be axially held between the two bearing blocks 36. The shaft is provided with an extension 38 passing through a bore 39 in the transformer leg 13. On the end of the extension 38 of the shaft 30 projecting outwardly a crank or handwheel may be mounted which permits to rotate the worm wheel and thereby to adjust the position of the coil in a very precise manner.

Instead of the crank a pulley or sprocket wheel may be mounted on the extension 38 in order to drive the shaft 30 from some controlling mechanism.

The above described construction provides an adjustability of the coil 15 which permits to adjust the transformation ratio within rather wide limits. More specifically the coil 15 may be moved from a position in which it is completely contained within the coil 12 to a position in which the distance between the coils is relatively large. In the position in which one coil is located within the other coil the maximum induction takes place and there is a direct inductive cooperation between the two windings of the coils to the maximum extent. When the coil 15 has been moved to a sufficient distance from the coil 12 by means of the mechanism as above described the induction between the coils is entirely eliminated and induction currents are produced solely by the variation of the magnetic flux which is produced by the primary coil. This permits a wide range of adjustability and also a high efficiency over the entire range on account of the fact that a closed transformer core frame is used.

Obviously, it does not make any difference whether the coil 15 or the coil 12 is the primary coil of the induction apparatus. Either of them may be used, the selection being determined by the number of turns, the available space and by other circumstances.

As above indicated, the transformer may also be used for an automatic voltage regulation in

connection with one of the well known devices which in this case may drive the shaft 30 in order to adjust the transformer for the required voltage.

5 Minor changes of an unessential nature, especially changes in the construction may be made without departing from the essence of the invention as defined in the adjoined claims.

Having described the invention, what is claimed as new is:

1. An adjustable transformer comprising a completely closed transformer core with two parallel legs, a primary and a secondary coil on one of said transformer legs, encircling the same, the primary coil being annular surrounding a hollow interior space between said core and said primary coil adapted to accommodate the secondary coil, said secondary coil being movable along said leg from a position in which one of the two coils substantially surround each other to a position in which they are at a distance from each other, a bracket attached to the smaller coil, a guiding and advancing means along the leg parallel to the coil encircled leg, means carried by said bracket for engaging said guiding and advancing means and further means for advancing said aforesaid means along said guiding and advancing means and along the transformer leg parallel to the coil encircled leg, thus moving the movable coil along the encircled leg.

2. An adjustable transformer as claimed in claim 1, wherein said guiding and advancing means consists of a rack attached to the leg parallel to the coil encircled leg and wherein the means engaging the aforesaid guiding and advancing means consists of a worm wheel, a rotatable shaft carrying said worm wheel and adapted to rotate the same, a yoke carrying said worm wheel, fixed to the said bracket and means for rotating said shaft.

3. An adjustable transformer comprising a completely closed transformer core with two parallel legs, a primary and a secondary coil on one of said two parallel legs encircling the same, the primary coil being fixed and annular, the inner surface of said annular coil being spaced from the transformer core to an extent corresponding to the outer diameter of the secondary coil, means for slidably seating and guiding said secondary coil on the leg of the transformer core encircled by the primary coil, and means for displacing the said secondary coil along the leg of the transformer core on which it is seated and along which it is guided, such displacing of the secondary coil moving the same from a position within the primary coil to a position outside and remote from the primary coil, said last named means including a member, displaceable along the second leg of the transformer core, the movement of which along the said leg is finely adjustable.
